UNITED STATES PATENT OFFICE.

RICHARD N. OAKMAN, OF NEW YORK, N. Y.

APPARATUS FOR CONTROLLING GAS-CONDUITS.

No. 813,577.

Specification of Letters Patent.

Patented Feb. 27, 1906.

Application filed June 19, 1905. Serial No. 265,884.

To all whom it may concern:

Be it known that I, RICHARD N. OAKMAN, a citizen of the United States, and a resident of the city, county, and State of New York, have 5 invented a new and useful Improvement in Apparatuses for Controlling Gas-Conduits, of which the following is a full description.

In a former application now pending, filed on the 27th day of May, 1905, and bearing 10 the Serial No. 262,567, I have shown and described a device for opening and closing the ports of a gas-conduit which includes a reciprocating piston having surfaces or slots upon its periphery to provide a communication to the passage-way leading to a burner for the escape and entrance of air from and to the rear end of the cylinders and adapted to accommodate devices for preventing the turning of the piston within the cylinders. 15 The piston in that device contains no through-way, either in its body or around its periphery, for the flow of gas to the burner, and is so arranged within the cylinder that its forward movement closes the lower port in the 20 conduit when the body of the piston is over this port and opens the port in its backward movement when the rear end of the piston has passed over and beyond the port, thus leaving the passage of gas free through the 25 cylinder. In the present device I use the same character of piston solid in the sense that it contains no throughway in or around the body, but differs therefrom in that it has no slot or plane surface removed from its 30 periphery. I combine this piston with a duct leading from the rear end of the cylinder to the passage-way to the burner and dispense entirely with devices for preventing the cylinder from turning.

40 The accompanying drawings illustrate the invention, of which—

Figure 1 is a vertical section of the device, showing the gas-ports open and a small duct or groove in the top of the cylinder leading 45 to the passage-way to the burner; Fig. 2, a cross-section of cylinder on line *a b*, Fig. 1, showing small groove in the top of the cylinder; Fig. 3, a vertical section showing piston at the other end of the cylinder with the ports 50 closed, a slot in the upper side of the bore of the standard, and a hole through the end of cylinder leading to the slot in the standard; Fig. 4, a view of the end of cylinder as constructed in Fig. 3; Fig. 5, a plan of cylinder 55 and piston, showing the upper gas-port in the cylinder and a slot through the cylinder from

its end to the port; Fig. 6, a cross-section of cylinder on line *c d* of Fig. 5.

1 is a post or standard, having a socket 2 for attachment to a gas-pipe. Through the 60 body of the standard is the bore 3, provided with a clear passage-way 6 to a burner 7. Within the bore is inserted the cylinder 8, provided with the ports 4 and 5, adjusted to correspond with the passage-way to the 65 burner, and is also provided with a nozzle 9 to connect with any of the well-known devices (not shown) for exhausting and compressing air or other fluid to reciprocate the piston 10, which is solid and closes ports 4 70 and 5 when impelled toward the rear of the cylinder or opens them when withdrawn until its end has passed beyond the ports, as shown in Fig. 1. In the rear end of the cylinder and leading thence to the passage-way 75 6 is shown, Figs. 1 and 2, a small groove 11, which permits the air at that end of the cylinder to escape through passage-way 6 when the piston is impelled forward and allows it to enter again behind the piston when withdrawn. A duct 12 is also shown in Figs. 3 and 4, slightly varying from that of Fig. 1. This duct is cut in the bore of the standard and runs into the passage-way 6. When the duct is formed in this way, I cut a small hole 80 13 at the end of the cylinder through its wall, communicating with duct 13. The form I prefer, however, is that shown in Figs. 5 and 6, which shows a slot 14, cut through this wall of the cylinder from the port 4 to the rear end 90 of the cylinder. This construction of the apparatus has many advantages. By making the piston solid (without a throughway) it may be made shorter, consequently lighter and more easily reciprocated. Having no 95 part of its periphery removed, a well-fitted piston will close both of the ports 4 and 5, and thus make a more perfect stoppage of the flow of gas through those ports, and by combining a piston thus constructed with a duct 100 leading from the end of the cylinder to the passage-way 6 dispenses with the necessity for preventing the piston from turning in the cylinder, as it will always present its full body to the ports in any event.

105 A pipe 15, having a small bore 16, leads from the socket 2 below the cylinder having its end 17, always lighted, located in the path of the gas from the burner 7.

What I claim is—

110 1. In an apparatus for controlling gas-conduits, a cylinder having openings or ports,

communicating with a gas-conduit, and provided with a solid reciprocating piston, to close the ports when its body covers them, and to open the ports when its end has passed 5 beyond them, in combination with a duct leading from the rear end of the cylinder to the gas-conduit.

2. In an apparatus for controlling gas-conduits, a cylinder having openings or ports 10 communicating with a gas-conduit, in combination with a solid reciprocating piston to open and close the ports, said cylinder pro-

vided with a slot in its upper wall, extending from its upper gas-port to the rear end of the cylinder.

In testimony whereof I, said RICHARD N. OAKMAN, have signed my name to this specification, in the presence of two subscribing witnesses, this 17th day of June, 1905.

RICHARD N. OAKMAN.
